[57] CLAIM

The ornamental design for an element of a shoe upper, as shown and described.

DESCRIPTION

FIG. 1 is a side elevational view of an element of a shoe upper showing my new design;

FIG. 2 is a front elevational view of the element of a shoe upper shown in FIG. 1;

FIG. 3 is a rear elevational view of the element of a shoe upper shown in FIG. 1; and,

FIG. 4 is a top plan view of the element of a shoe upper shown in FIG. 1.

The broken line showings of the circle shapes at the base of the element and the remainder of the shoe are for illustration purposes only and form no part of the claimed design.
